Primary Examiner — Cynthia Underwood*(74) Attorney, Agent, or Firm* — Patton Boggs LLP(57) **CLAIM**

The ornamental design for a locking double carabineer, as shown and described.

DESCRIPTION

FIG. 1 is a front perspective view of a locking double carabineer;

FIG. 2 is a rear perspective view of the locking double carabineer of FIG. 1;

FIG. 3 is a front view of the locking double carabineer of FIG. 1;

FIG. 4 is a rear view of the locking double carabineer of FIG. 1;

FIG. 5 is a left view of the locking double carabineer of FIG. 1;

FIG. 6 is a right view of the locking double carabineer of FIG. 1;

FIG. 7 is a top view of the locking double carabineer of FIG. 1; and,

FIG. 8 is a bottom view of the locking double carabineer of FIG. 1.
